Des. 228,795
Patented Oct. 23, 1973

228,795

WIRELESS LIGHTING FIXTURE

Curtiss M. Peasley, 25 Boulder Drive,
Burlington, Mass. 01803

Filed Jan. 10, 1972, Ser. No. 216,888

Term of patent 14 years

Int. Cl. D26—05

U.S. Cl. D48—4 B

Fig. 1.

Fig. 2.

Fig. 3.

Fig. 4.

FIG. 1 is a perspective view showing the front, top and right-hand sides of the wireless lighting fixture of my new design;

FIG. 2 is another perspective view showing the front, bottom and left-hand sides of my wireless lighting fixture;

FIG. 3 is a side view of my wireless lighting fixture; and

FIG. 4 is a rear view of my wireless lighting fixture.

The chain is broken away in FIGS. 2 and 4 for convenience of illustration.

I claim:

The ornamental design for a wireless lighting fixture, substantially as shown and described.
